UNITED STATES PATENT OFFICE.

FRANK STREICH AND PAUL E. FRANKE, OF JOLIET, ILLINOIS, ASSIGNORS TO UNION WRAPPING MACHINE COMPANY, OF JOLIET, ILLINOIS, A CORPORATION OF ILLINOIS.

BREAD WRAPPING AND SEALING MACHINE.

1,110,083.

Specification of Letters Patent.

Patented Sept. 8, 1914.

Application filed November 19, 1913. Serial No. 801,783.

To all whom it may concern:

Be it known that we, FRANK STREICH and PAUL E. FRANKE, both citizens of the United States, and residents of Joliet, county of Will, and State of Illinois, have invented 5 certain new and useful Improvements in Bread Wrapping and Sealing Machines, of which the following is declared to be a full, clear, and exact description.

10 This invention relates to wrapping and sealing machines, and in its present form has been designed for wrapping and sealing commodities such as bread, or other like goods, although it will be perfectly obvious 15 from the following specification that it may be employed for wrapping and sealing many other articles.

The primary object of this invention is to provide a wrapper and sealer of improved 20 construction, one which is simple in construction and operation and one which is capable of folding the ends of a wrapper in such a manner that the folds may be secured together by the application of heat thereto, 25 when paraffined or waxed paper wrappers are used, or by the application of paste or glue when other forms of wrappers are used to contain the commodity.

The invention consists in the several novel 30 features of construction, arrangement and combination of parts hereinafter fully set forth and claimed.

One embodiment of the invention is clearly illustrated in the drawings accompanying this specification of which:—

Figure 1, is a plan of a machine containing the preferred form of the invention; Fig. 2, is a side elevation thereof; Fig. 3, is a longitudinal section taken on the line 3—3, 35 Fig. 1, showing the operating parts in a different position; Fig. 4, is a detail, vertical cross-section taken on the line 4—4, Fig. 1; Fig. 5, is a detail, vertical cross-section taken on line 5—5, Fig. 1; Fig. 6, is a perspective view of a wrapper showing the first fold; Fig. 7, is a similar view showing the second fold; Fig. 8, is a similar view showing the third fold, and Fig. 9, is a similar view showing the fourth and last fold.

50 In the embodiment of the invention illustrated in said drawings, 10, designates frame work upon which is supported a table 11, comprising two horizontal leaves 12, 12^a, which carry the folding and sealing macha- 55 nisms, and which are capable of lateral ad-

justment with respect to each other, to accommodate parcels or articles of various lengths. Upon the forward or receiving end of the table is mechanism for folding the first and second folds, beyond which is 60 the means for making the third fold, and farther on is the mechanism for making the fourth and last fold. In order that these several instrumentalities may be clearly understood, we shall proceed to describe each 65 in detail.

The first fold.—Projecting up from the table 11, are two oppositely disposed, vertically reciprocatory, bottom flap folders 13, each having a curved upper edge, (see Fig. 2.) 70 and each guided to move in a vertical direction; each folder 13, is shown as formed with a vertical slot 14, through which extends a screw 15, secured in the outer edge of the table leaves 12, 12^a, and the head of 75 said screw holds the folder in position against the side of the table. The lower end of each bottom flap folder 13, is connected to a lever 16, pivoted upon a bracket 17, secured to the underside of the table and said 80 levers 16, are connected to an operating lever, here shown in the form of a hand lever 18, pivoted to a bracket 19, secured to the underside of the leaf 12. The connection between the levers 16, and hand lever 18, is shown in 85 the form of a transversely extending rod 20, extending through the levers 16, 18, and secured against lateral movement with respect to the levers, by means of collars 20^a, one on either side of the hand lever 18. The hand 90 lever has a slot 18^a, for the rod 20. Depression of the levers 16, 18, acts to draw down or lower the bottom flap folders. Tension springs 21, one attached to each lever 16, and to the table, act to return the levers to raised 95 position when released.

The function of the folders 13, is to fold up the bottom flaps, *a*, of the wrapper A, against the ends of the article, contained in the wrapper (see Fig. 6.), and this operation 100 is performed as follows:—The article, for instance a loaf of bread, is placed on a rectangular sheet of paper (preferably paraffined or waxed paper) and the same is folded around the loaf, bringing the edges 105 past each other at the bottom of the loaf. The loaf with its wrapper thus folded around it, is placed over the flap folders 13, and pressed down to the table; the folders 13, fold up the bottom flaps *a*, of the wrap- 110

per, bringing them against the ends of the loaf, as seen in Fig. 6, and the loaf is held in this position while the first side fold is made.

5 *The first side fold.*—In front of the bottom flap folder 13, and in alinement therewith are two side flap folders 22 (see Figs. 2 and 8), each of which is supported and guided by a bracket 23, secured to the upper 10 face of the table, and each side flap folder is guided to move toward and along the end of the loaf. Each folder 22, has a longitudinally extending slot 24, through which extends a bolt 25, secured in the bracket 23, 15 and said folder rides on said bolt in moving through its operative strokes. One extreme end of each side flap folder 22, is connected to a rock lever 26, pivoted to a depending arm 27, of the bracket 23, and receives its 20 motion therefrom, and in operation said rock lever 26, is moved from the position seen in Fig. 2, to that seen in Fig. 3, and back again to force the side flap folder 22, across the end of the loaf and fold the protruding side 25 flap *b*, theretacross, as seen in Fig. 7. The end of each rock lever, opposite its connection with the side flap folder 22, is provided with a U shaped slot 28, through which extends the rod 20, that connects the levers 16, 30 18, and said rock levers 26, are actuated by said hand lever through the hand lever connection 20.

Referring to Fig. 2, the vertical part of the U slot 28, permits a certain amount of 35 downward movement of the operating lever and bottom flap folders, before the operating lever begins to move the rock levers and side flap folders, whereby the tops of the bottom flap folders may be lowered sufficiently to 40 permit the side flap folders to pass over them and across the ends of the loaf; the bottom flap folders holding the bottom flaps in place until the side flap folders have begun to fold over the side flaps referred to. This 45 side flap fold is made by depressing the hand lever, after the loaf of bread with its wrapper has been placed upon the table between the bottom flap folders, as herebefore explained.

50 *The second side flap fold or third fold.*—Beyond the bottom flap folders, 13, are two horizontally swinging wings or second side flap folders 29, which extend across the table and are pivotally supported thereon 55 by vertical pins or pivot members 30, secured in the table. Each wing or side flap folder 29, is spring pressed into position across the table by a spring 31, surrounding the pin 30, and having one end fastened to 60 the table and the other pressing against the side of the wing. A stop in the form of a screw 32, lies in the path of each wing and arrests its movement (caused by the spring) so as to hold it across the table in position 65 to be struck by the loaf when moved past it.

The bottom and first side fold having been made, the operator, while holding the operating lever depressed, moves the loaf along the table and past the wings, which are thereby swung back into alinement with the 70 bottom flap folders, and as the loaf passes them they engage and fold back the second side flaps *c*, to the position seen in Fig. 8, holding them in such position until the next operation of the machine. After the 75 loaf has been moved past the wings, the springs 31, return the wings to normal position.

75 *The top flap fold.*—Beyond the wings 29, are the top flap folders 33, which, as shown, 80 comprise vertical plates extending in alinement with the bottom and first side flap folders, and having angularly disposed flanges 34, projecting outward and laterally therefrom (see Figs. 1 and 4). Each top 85 flap folder is carried by a pair of movable bars 35, (see Fig. 2.) pivotally secured thereto and pivotally connected to a side wall section 36, secured to the table in alinement with the top flap folders. The top flap 90 folders 33, are operated from the levers 16, 18, by links 37, here shown as connected to the uppermost bars 35, and to the levers 16, at 38. Normally, said top flap folders occupy the position seen in Fig. 2, but when 95 the operating lever is depressed to make the first side flap fold, the rear ends of the levers 16, are raised and the top flap folders lifted to the position seen in Fig. 3, the same being somewhat above the top of a loaf of 100 bread which is to be wrapped. The lever is held in its depressed condition until the loaf has been moved past the second side flap folders 29, and to a position between the top flap folders, with the top flaps *d*, projecting under the same, whereupon the operating lever is released or raised, the links 105 37, are drawn down, the bars 35, swung down, carrying with them the top flap folders, which fold down the top flaps against the 110 others, as seen in Fig. 9.

115 This completes the flap folding operations. Beyond the wall sections 36, and in alinement therewith, are heat applying members 39, which are secured to the table 115 and comprise heating plates and some form of heating means (preferably electric) and below said heat applying members 39, is a bottom heat applying member 40, whose upper face is approximately flush with the 120 upper face of the table, and said bottom heating member is secured to the leaf 12, and extends under the end flap heating members 39. Beyond the heat applying plates are cooling plates 50, between which the 125 wrapped and sealed loaves are moved after the flaps have been heated to partly melt the paraffin, and said cooling plates hold the flaps together and against the ends of the loaf until the paraffin has cooled and set. 130

To accommodate different lengths of loaves or other articles to be wrapped and sealed, the table is made laterally adjustable, and as one set of flap folders and end flap 5 sealer is carried by each leaf, the set carried by the leaf 12^a, may be moved toward or away from the other set to vary the distance between them. The adjustment of the table and parts carried thereon, comprises means 10 as follows. The supporting frame 10, has slotted cross bars, one of which is seen at 41, to which is secured the leaf 12. Sliding in each of the slots of said cross bars 41, is a bar 42, secured to the movable leaf 12^a, and 15 having rack teeth 43, on its underside, meshing with the teeth of a toothed wheel 44, on a rod 45, journaled in the frame 10. A hand wheel 46, on said rod furnishes means for turning the rod to rotate the toothed wheels 20 and move the rack bars and leaf secured thereto.

The rod 20, which connects the hand lever with the flap folder levers 16, and rock lever 26, protrudes beyond the rock lever 26, on 25 the movable leaf to permit lateral adjustment of said leaf without disengaging the rock lever from said rod. The flap folding levers 16, hand lever 18, and rod 20, may comprise one form of operating means or 30 mechanism for actuating the flap folders, and if desired, may be in the form of a hand operated lever or foot power operated lever, as desired.

From the above description it is readily 35 apparent that loaves of bread or other articles may be wrapped and sealed with ease, with neatness and with great rapidity. When paraffined paper wrappers are used, the heat of the heat applying plates serves 40 to heat and partly melt the paraffin, and because of the pressure of the cooling plates against the flaps, the latter are secured together when cooled, thereby sealing the contents and dispensing with string or other 45 means for tying the wrapper on the loaf.

More or less variation of the several details of construction are possible without departing from the spirit of this invention and we desire, therefore, not to limit ourselves 50 to the exact form shown and described, but intend in the following claims, to point out all of the novel features disclosed herein.

We claim as new and desire to secure by Letters Patent:

55 1. A wrapping machine, comprising a table for receiving the articles to be wrapped, oppositely disposed, bottom flap folders, first side flap folders and top flap folders supported thereon, an operating lever and operative connections between said flap folders 60 and operating lever, there being a limited amount of lost motion in the connections between the first side flap folders and operating levers, whereby the bottom and top flap folders may be actuated simultane-

ously, and the first side flap folders may be actuated thereafter by and from said operating lever.

2. A wrapping machine, comprising a table for receiving the articles to be wrapped, oppositely disposed, vertically reciprocable, bottom flap folders, first side flap folders movable thereacross, and vertically reciprocable, top flap folders, an operating lever, operative connections between said bottom flap folders, side flap folders and operating lever on one side of its fulcrum, and operative connections between said top flap folder and said operating lever on the other side of its fulcrum. 80

3. A wrapping machine, comprising a table for supporting the articles to be wrapped, oppositely disposed bottom flap folders, first side flap folders and top flap folders supported by said table, operating mechanism therefor, and transversely extending, oppositely disposed second side flap folders, fulcrumed between their ends upon said table between the bottom flap folders and top flap folders, and lying in the path 90 of movement of the article from the bottom flap folders to the top flap folders.

4. A wrapping machine, comprising a table for receiving the articles to be wrapped, oppositely disposed bottom flap folders normally projecting above said table, and guided to move down therefrom, a pair of oppositely disposed, first side flap folders supported on said table in alinement with the bottom flap folders, manually actuated 100 levers fulcrumed below the table, and connected to said bottom flap folders, a rock lever connected to each side flap folder, and connecting means on said levers engaging said rock levers, and operating to rock the 105 rock levers and therewith reciprocate the first side flap folders over the bottom flap folders to fold the first side flaps across the end of the article.

5. A wrapping machine, comprising a 110 table for receiving the articles to be wrapped, oppositely disposed, bottom flap folders at the sides of the table, each having means for guiding it to move vertically manually operated, operating means fulcrumed at the 115 underside of the table and connected to said bottom flap folders, and a spring for raising said operating means and yieldingly holding the same in raised position and therewith holding the bottom flap folders in 120 raised position to engage and fold up the bottom flaps of the wrapper.

6. A wrapping machine comprising a table for receiving the articles to be wrapped, a pair of oppositely disposed, flat, first side 125 flap folders, each having a longitudinally extending slot, a support extending through each slot, said folders being capable of reciprocating on said supports, rock levers, one for each folder, and connected to one end 130

thereof, and operating means for rocking said rock levers, there being a limited amount of lost motion between the operating means and rock levers.

5 7. A wrapping machine, comprising a table for receiving the articles to be wrapped, oppositely disposed bottom flap folders, oppositely disposed, first side flap folders, each having a longitudinally extending slot, a 10 support extending through each slot, and the side flap folders being reciprocable thereon, rock levers, one for each side flap folder, and connected thereto at one end, levers connected to and actuating the bottom flap folders and operative connections between said 15 levers and rock levers, having a limited amount of lost motion, whereby the levers may be depressed to partly lower the bottom flap folders in advance of the side flap 20 folders.

8. A wrapping machine, comprising a table for receiving the articles to be wrapped, oppositely disposed, bottom flap folders, oppositely disposed, first side flap folders, each having a longitudinally extending slot, a support extending through each slot, and the side flap folders being reciprocable thereon, rock levers, one for each side flap folder, and connected thereto at one end, 25 each rock lever being formed with a "U" shaped slot at its other end, lever mechanism connected to the bottom flap folders, and having means extending through the "U" shaped slots of the rock levers, substantially 30 as and for the purpose set forth.

9. A wrapping machine, comprising a table for receiving the articles to be wrapped, oppositely disposed, horizontally swinging, second side flap folders, pivotally supported 40 on said table, springs, one for each folder, operating to yieldingly hold the folders in position across the table, stops for limiting the action of said springs, and top flap folders beyond said second side flap folders, 45 the latter acting to fold back the second side flaps, and capable of being swung under the top flap folders to act as retaining members for said flaps when the article is moved to a position under the top flap 50 folders.

10. A wrapping machine, comprising a table for receiving the articles to be wrapped, oppositely disposed, top flap folders, oppositely disposed supports in alignment therewith, parallel movement bars pivotally connecting said top flap folders with said supports, manually operated levers fulcrumed below the table, and links for connecting said levers with said folders.

11. A wrapping machine, comprising a table for receiving the articles to be wrapped, oppositely disposed, top flap folders, each having a vertical side and a lateral flange at the bottom thereof, a combined support 55 and operating means for each of said

folders, comprising a pair of parallel, pivotally supported bars, pivotally connected to the folder, a link connected to one bar of each pair, and a lever for reciprocating the link.

70

12. A wrapping machine, comprising a table for receiving the articles to be wrapped, oppositely disposed bottom flap folders, first flap folders and top flap folders, one set at each side of the table and in substantial alinement with each other, and operating means connected therewith and operating to simultaneously depress the bottom flap folders, move the first flap folders thereabove, and raise the top flap folders.

80

13. A wrapping machine, comprising a table for receiving the articles to be wrapped, oppositely disposed bottom flap folders, first side flap folders and top flap folders, one set at each side of the table and in substantial alinement with each other, levers fulcrumed between their ends on supports located below the table, connecting means between each lever and its bottom flap folder and first side flap folder at one side of its fulcrum, and connecting means between each lever and its top flap folder at the other side of its fulcrum.

85

14. A wrapping machine, comprising a table having two laterally adjustable leaves for receiving the articles to be wrapped, a set of bottom flap, first side flap and top flap folders supported at the side of each leaf, a lever fulcrumed at each side of the table and connections between each lever and the folders on its side of the table, an operating lever, and a connection between said operating lever and the other levers having a sliding connection with one of said levers.

100

15. A wrapping and sealing machine, comprising a table, oppositely disposed, bottom flap folders, first side flap folders and top flap folders, operating means therefor and oppositely disposed, second side flap folders between the bottom flap folders and top flap folders, oppositely disposed, heating plates in alinement with the flap folders, and located beyond the top flap folders, a bottom heating plate below said oppositely disposed heating plates, said heating plates operating to heat the wrapper after the folds have been made, and oppositely disposed cooling plates beyond the heating plates.

105

16. A wrapping machine, comprising a table having two laterally separable leaves for receiving articles to be wrapped; bottom, first side, second side and top flap folders mounted on each leaf, those on one leaf being oppositely disposed with respect to those on the other leaf, mechanism carried by each leaf for actuating said bottom, first side and top flap folders and an operating lever connected to both sets of mechanisms.

110

17. A wrapping machine, comprising a

115

table having two laterally separable leaves for receiving articles to be wrapped; bottom, first side, second side and top flap folders mounted on each leaf, folder actuating

5 mechanisms for the bottom, first side and top flap folders carried by each leaf, means for connecting said mechanisms, and having an

adjustable connection with one of said mechanisms, and an operating lever therefor.
